UNITED STATES PATENT OFFICE.

JOHN BERRY, OF BIDDEFORD, MAINE.

PHARMACEUTICAL STILL.

SPECIFICATION forming part of Letters Patent No. 313,163, dated March 3, 1885.

Application filed May 9, 1884. (No model.)

To all whom it may concern:

Be it known that I, JOHN BERRY, of Biddeford, in the county of York and State of Maine, have invented a new and useful Improvement 5 in Pharmaceutical Stills; and I do hereby declare that the following is a full, clear, and exact description of the same.

My invention relates to pharmaceutical stills, the general object of which is greater 10 simplicity and compactness and rapidity in the operation, all of which is set forth fully hereinafter.

In the accompanying drawing, the figure represents a central vertical section of the apparatus. In this figure the boiler in which the liquid is evaporated is at *d*. It may be made rounded or in any convenient form or of any 15 convenient size. The heat may be applied to it by a spirit-lamp or by any well-known or 20 suitable apparatus. A threaded pipe-extension (shown at *L*) serves to connect the condenser to the boiler, the lower part of the condenser being fitted for union for the threaded extension *L*. The condenser consists of 25 the condensing-chamber *C* of the outer jacket, *O*, there being between the chamber *C* and the jacket a space or chamber, *H*, which very 30 nearly surrounds the entire condensing-chamber. Water or other cool liquid is admitted 35 from a suitable head into a chamber, *H*, through a pipe, *F*, and escapes through the pipe *K*. A nozzle, *M*, connects the interior of the boiler with the interior of the condensing-chamber. This pipe is surrounded within 40 the condensing-chamber by a jacket, *1 1*, and outside of the condensing-chamber, and between it and the outer or main jacket, *O*, by a jacket, *2 2*, these jackets *1* and *2* forming small annular chambers *a*. These protect the 45 tube *M* from the effect of the cold water in chamber *H* and cold air in chamber *C*, and prevent the vapor from condensing in said tube and running back to the boiler. The discharge pipe *h* extends from the bottom *D* of the condensing-chamber through the cham-

ber *H*, and communicates with the pipe leading to the receiving-vessel *E*. As the pipe *h* passes through the chamber in which the cold water circulates, the condensed liquid is cooled while on its way to the receiving-vessel. The 50 vapor as it condenses within the chamber *C* falls to the bottom of chamber *C* and escapes through the pipe, as described, and none of it can run back into the boiler by reason of the construction of the protecting-chambers *a a* 55 and the nearness of the whole condensing apparatus to the boiler. I provide in the top of the boiler a thermometer, *P*. This I set within a plug which is adapted to the filling-orifice. The bulb of the thermometer projects 60 within the upper part of the boiler-space above the line of the liquid.

The apparatus may be made of any desired size without affecting its operation.

The general construction renders the apparatus exceedingly compact and convenient in addition to the advantages heretofore enumerated.

I claim as my invention—

1. A boiler, *d*, provided with an extension, *L*, connected directly to the bottom of the condensing apparatus, in combination with the tube *M*, surrounded by jackets *1 2*, and opening into the interior of the condensing-chamber, substantially as described. 75

2. The boiler *d*, provided with the threaded extension *L*, and the pipe *M*, combined with the condensing-chamber *C* and jacket *O* and jackets *1* and *2*, substantially as described.

3. The combination, with the chambers *C* 80 and jackets *O*, of tube *M*, jackets *1 2*, and the pipe *h*, substantially as described.

In testimony whereof I have signed my name to this specification in the presence of two subscribing witnesses.

JOHN BERRY.

Witnesses:

WILLIAM MORAN,
EDWARD L. COWAN.
